UNITED STATES PATENT OFFICE.

PHILIPPO L. E. DEL FUNGO-GIERA, OF NEW YORK, N. Y.

ANCHOR.

Specification of Letters Patent.

Patented July 2, 1918.

1,271,442.

Application filed February 3, 1917, Serial No. 146,409.

Renewed May 31, 1918. Serial No. 237,625.

To all whom it may concern:

Be it known that I, PHILIPPO L. E. DEL FUNGO-GIERA, a citizen of the Republic of Switzerland, and a resident of New York, 5 borough of Manhattan, county and State of New York, have invented certain new and useful Improvements in Anchors, of which the following is a specification.

My invention relates to anchors, particularly for the purpose of anchoring buoys, floating mines, submarine supply containers, etc., and the main object thereof is to provide an anchor which combines the advantages of the gravity, the mushroom, and the ballasted types, whereby the mooring of either floating or submerged objects is positively insured regardless of weather or water flow conditions.

My invention is fully described in the following specification, of which the accompanying drawings form a part, in which like characters refer to like parts in each of the views, and in which:—

Figure 1 is a view of my anchor, partly in section, illustrated in connection with a submarine supply container; and Fig. 2 is a top plan view of the anchor alone.

Referring to the drawings, 3 represents a submarine supply container as shown and described in my application for Letters Patent of the United States filed on the 28th day of August, 1916, Serial No. 117,196, from which a cable 4 descends to and is secured to an anchor 5.

The anchor 5 consists of a central member 6 having means 7 thereon for cable connection and having a mushroom member 8 at the bottom thereof continued, as shown at 9, to form a saucer-shaped member adapted 40 to have sand or other solids washed thereinto to add to the weight of the anchor and thereby increase its stability, whereas the mushroom member 8 acts as a suction cup and positively insures the necessary stability when the anchor is used for mooring mines and supply containers, or partially submerged observation vessels, or partially submerged signals or guides, as in a time of war.

While mushroom anchors have heretofore been employed, as well as cup-shaped anchors adapted to receive sand and the like, each of these serves only in the one way for which it was designed, whereas my anchor possesses the advantages of three distinct types, as above stated.

The web portion shown at 10, joining the mushroom member 8 to the saucer member 9 is a very important feature of the anchor, as this relatively short web portion makes a utilization of the mushroom and cup types of anchors in combined form possible, and the member 6 is also highly important, and much as it may be made of any desired weight to act as an anchoring means b

My anchor is very simple, though high efficient, and is preferably made of steel though, obviously, I am not limited to exact material of which it is composed, if desired, I may reverse the positions of members 8 and 9 by simply turning the anchor upside down and having the member 6 seated in the dished member 8, the being similar although I prefer the f

tion illustrated.

Having fully described my invention I claim as new, and desire to secure Letters Patent, is:—

1. An anchor, comprising a mushroom member, a web member, a concentric cup shaped member, and means for securing said anchor.

2. An anchor, comprising a central shaped member, a web member, an annular member, and means for connecting said anchor.

3. An anchor, comprising a central shaped member, a cup-shaped web member connecting said central member and means for securing said anchor.

PHILIPPO L. E. DEL
